UNITED STATES PATENT OFFICE.

KENNETH H. KIEFER, OF BALTIMORE, MARYLAND.

METHOD AND MEANS OF EXTINGUISHING FIRES.

No Drawing.

Application filed March 14, 1923. Serial No. 825,172.

This invention relates to a method and means of extinguishing fires and has special application to the extinction of fires which develop, more or less spontaneously, in bodies of granular, fragmentary or other loosely packed combustible material that contain air, and which are disposed in more or less confined places, for example, bodies of coal, rags, sawdust, grain, hay, etc., in barges, 5 bunkers, holds, bins, pits, etc.

Among the objects of this invention is the provision of a method and means for effectively extinguishing fires occurring in such bodies of materials and to remove the dangers, hazards and other disagreeable features incident to the methods and means heretofore employed for extinguishing fires.

More specifically, it is an object of this invention to provide a method and means whereby an operator may readily ascertain when the fire is extinguished in the interior of such bodies of material so as to enable the operator to correctly judge when to discontinue the application of the fire extinguisher, thereby avoiding unnecessary waste 20 of the extinguishing material.

A further object of this invention is to provide a method and means whereby it may be readily and conveniently determined when a body of combustible material which has been treated with the fire extinguisher ceases to evolve noxious, toxic and otherwise objectionable fumes, thus enabling the operator to determine whether or not to enter in the vicinity of such material, or whether precautionary measures are necessary before such entry.

Fire extinguishers have heretofore been prepared from the liquid, chlorinated, aliphatic hydrocarbons, such as CCl_4 , $CHCl_3$, etc. These fire extinguishing liquids have been applied to the bodies of burning or smouldering material, the vapors of such liquids serving to displace the air from such bodies and forming a lingering, coherent and enveloping atmosphere which does not support combustion. The disadvantages of using these materials have been that the vapors are practically non-detectable, owing to 40 their substantially negligible visibility. This has resulted in the use of a large excess of the fire extinguishing liquid beyond that necessary for the extinction of the fire because of the impracticability of ascertaining when 45 a sufficient amount of the fire extinguisher

has been employed. Also, in view of the noxious, toxic and otherwise objectionable character of these vapors and decomposition products thereof occurring during the fire extinguishing operation, fatalities and other 50 physical injuries have occurred to persons entering in the vicinity of the bodies of material which have been treated by these fire extinguishers, due chiefly to the fact that such persons were unable to observe whether 55 these fumes were issuing from such bodies and had no means to warn them of their danger.

In practicing my invention, I add to a halogenated hydrocarbon of the aliphatic 70 series, such as CCl_4 , $CHCl_3$, C_2Cl_6 , etc., a substance which will give warning when a sufficient amount of the fire extinguisher has been applied to complete the operation and also give warning of the issuance of the toxic 75 or other objectionable gases from the material from which the fire has been extinguished.

For this purpose, I employ a substance 80 which upon issuing into the atmosphere will react with a constituent thereof to form a product which may be easily and conveniently detected by its visibility. The preferred materials which I employ are the liquid metallic substances which fume in the air 85 and do not react with the halogenated hydrocarbon, for example, $TiCl_4$, $TiCl_3$, and $SiCl_4$, used either singly or in combination, and I add such material to the chlorinated hydrocarbon, such as CCl_4 . This results in 90 a substantially homogeneous liquid mixture. These metallic halides, upon issuing into the air react with the water vapor of the air to form a dense cloud or smoke that is readily 95 visible.

A specific example of preparing my fire extinguishing composition is as follows. To a quantity of CCl_4 , there is added about 5 to 25 per cent by volume of $TiCl_4$. The 100 quantity of the latter may be varied, according to the particular conditions but in general I employ about 10 per cent. A sufficient quantity of the $TiCl_4$ should be present to give the necessary warning, but for economic reasons it is not necessary to have 105 an excess of the $TiCl_4$ beyond that required to give sufficient warning. The mixture is liquid at ordinary temperatures, will not freeze under severe weather conditions, gives 110 a large volume of vapor which is non-com-

bustible and heavy enough to blanket the air from the fire and is visible.

In using my fire extinguishing composition, it is preferably introduced into the heart of the fire by means of a tube or pipe in the form of a spray until white fumes are observed at the surface of the body of the material being treated. The CCl_4 and TiCl_4 , upon reaching the fire become vaporized, and since these vapors are heavier than air they gravitate and displace the air. On further addition of the fire extinguisher, there being no more air to displace, the vaporized fire extinguishing composition, which may be partly decomposed, will rise and when these vapors reach the surface the air will have been practically driven out from the pile. Upon reaching the surface, the TiCl_4 in the fire extinguishing vapors will react with the moisture of the air to form a dense cloud or smoke, thus serving as a warning or signal that the air has been displaced from the pile, that the fire has been extinguished and that further addition of the fire extinguisher to the pile is unnecessary. This also serves as a warning that the toxic, noxious and objectionable fumes are issuing from the pile and indicates to the operator such danger. When the smoke no longer appears upon the surface of the pile, the operator knows that no more toxic or objectionable fumes are issuing from the pile and that it is safe to go to the pile for whatever purpose he may deem necessary.

My fire extinguishing composition should be stored in an air-tight container such as tin or glass, but I prefer to use metal cans, which are sealed against the entry of air. These cans may be provided with fusible plugs and, if it is desired to protect a pile of material against destruction by fire due to spontaneous combustion a metal can having the fusible plug and containing my fire extinguishing liquid may be placed within the center of the pile and if a fire develops the plug will fuse and allow the liquid to pass out of the container and extinguish the fire. The vapors of the fire extinguisher rising to the top of the pile will form a cloud or smoke upon reaching the atmosphere and thus give warning that a fire has taken place within the pile and that toxic and objectionable gases are issuing from the pile.

The present invention is not limited to the specific details set forth in the foregoing examples which should be construed as illustrative and not by way of limitation, and in view of the numerous modifications which may be effected therein without departing from the spirit and scope of this invention it is desired that only such limitations be imposed as are indicated in the appended claims.

I claim as my invention:

1. In a fire extinguisher, a non-combustible, non-flammable, non-aqueous liquid comprising a warning agent for readily indicating when a sufficient quantity of the fire extinguisher has been applied to complete the operation, said warning agent being dissolved in a halogenated aliphatic hydrocarbon. 65

2. In a fire extinguisher, a non-combustible, non-flammable, non-aqueous liquid comprising a warning agent for readily indicating the issuance of toxic, noxious and objectionable gases from the material from which the fire has been extinguished, said warning agent being dissolved in a halogenated aliphatic hydrocarbon. 75 80

3. In a fire extinguisher, a non-combustible, non-flammable, non-aqueous liquid comprising a warning agent for readily indicating when a sufficient quantity of the fire extinguisher has been applied to complete the operation and the issuance of toxic, noxious and objectionable gases from the material from which the fire has been extinguished, said warning agent being dissolved 85 90 in a halogenated aliphatic hydrocarbon. 95

4. In a fire extinguisher, a non-combustible, non-flammable, non-aqueous liquid comprising a substance which readily forms with water vapor a smoke readily detectable by its visibility, said substance being dissolved in a halogenated aliphatic hydrocarbon. 100 105

5. In a fire extinguisher, a non-combustible, non-flammable liquid comprising a halide of an element of the fourth group of the periodic table having an atomic weight of 25-125, said halide being dissolved in a halogenated aliphatic hydrocarbon. 110

6. In a fire extinguisher, a non-combustible, non-flammable liquid comprising a chloride of an element of the fourth group of the periodic table having an atomic weight of 25-50, said chloride being dissolved in a halogenated aliphatic hydrocarbon. 115 120

7. In a fire extinguisher, a non-combustible, non-flammable, non-aqueous liquid comprising a halogenated aliphatic hydrocarbon having in solution a substance which readily forms with a constituent of the atmosphere a product readily detectable by its visibility. 125

8. In a fire extinguisher, a non-combustible, non-flammable, non-aqueous liquid comprising a halogenated aliphatic hydrocarbon in solution with a halide of an element of the fourth group of the periodic table having an atomic weight of 25-50. 130

9. In a fire extinguisher, a non-combustible, non-flammable, non-aqueous liquid comprising a halogenated aliphatic hydrocarbon in solution with titanium tetrachloride. 135

10. In a fire extinguisher, a non-combusti-

- ble, non-flammable liquid comprising carbon tetrachloride and titanium tetrachloride.
11. In a process of extinguishing fires within bodies of granular combustible material disposed in barges, holds, bins, bunkers, pits, and other confined places, introducing into the burning material a non-combustible, non-flammable, non-aqueous liquid comprising a substance which readily forms with a constituent of the atmosphere a product readily detectable by its visibility until a cloud or smoke appears on the surface of the granular material.
12. In a process of extinguishing fires within bodies of granular combustible material disposed in barges, holds, bins, bunkers, pits, and other confined places, introducing into the burning material a spray of a non-combustible, non-flammable, non-aqueous liquid comprising a substance which readily forms with water vapor a smoke readily detectable by its visibility and continuing said spray until a cloud or smoke appears on the surface of the granular material.
13. In a process of extinguishing fires from bodies of granular combustible material disposed in barges, holds, bins, bunkers, pits and other confined places, introducing into the burning material a non-combustible, non-flammable, non-aqueous liquid comprising a halide of an element of the fourth group of the periodic table having an atomic weight of 25-125.
14. In a process of extinguishing fires within bodies of granular combustible material disposed in barges, holds, bins, bunkers, pits, and other confined places, introducing into the burning material a non-combustible, non-flammable, non-aqueous liquid comprising titanium tetrachloride until a cloud or smoke appears on the surface of the granular material.
15. In a process of extinguishing fires within bodies of granular combustible material disposed in barges, holds, bins, bunkers, pits, and other confined places, introducing into the burning material a spray of a non-combustible, non-flammable, non-aqueous liquid comprising a halogenated aliphatic hydrocarbon having in a solution a substance which readily forms with a constituent of the atmosphere a product readily detectable by its visibility and continuing said spray until a cloud or smoke appears on the surface of the granular material.
16. In a process of extinguishing fires within bodies of granular combustible material disposed in barges, holds, bins, bunkers, pits, and other confined places, introducing into the burning material a non-combustible, non-flammable, non-aqueous liquid comprising a halogenated aliphatic hydrocarbon having in solution a substance which readily forms with water vapor a smoke readily detectable by its visibility until a cloud or smoke appears on the surface of the granular material.
17. In a process of extinguishing fires within bodies of granular material disposed in barges, holds, bins, bunkers, pits and other confined places, introducing into the burning material a non-combustible, non-flammable, non-aqueous liquid comprising a halogenated, aliphatic hydrocarbon having in solution a halide of an element of the fourth group of the periodic table having an atomic weight of 25-50, until a cloud or smoke appears on the surface of the granular material.
18. In a process of extinguishing fires within bodies of granular combustible material disposed in barges, holds, bins, bunkers, pits, and other confined places, introducing into the burning material a spray of a non-combustible, non-flammable liquid comprising carbon tetrachloride and titanium tetrachloride and continuing said spray until a cloud or smoke appears on the surface of the granular material.

In testimony whereof I affix my signature.

KENNETH H. KIEFER.
